United States Patent Office

Des. 211,842
Patented July 30, 1968

211,842

CARRIER FOR BAKERY GOODS OR THE LIKE

Stephen M. Vilegi, Chester, and Louis H. Peters, Somerville, N.J., assignors to Union Carbide Corporation, a corporation of New York

Filed Sept. 26, 1967, Ser. No. 8,741

Term of patent 14 years

(Cl. D87—1)

FIG. I.

FIG.2.

FIG.3.

FIG. 4.

FIG. 5.

FIG. 6.

FIGURE 1 is an isometric view of a carrier for bakery goods or the like showing our new design;

FIGURE 2 is a front plan view thereof of FIGURE 1;
 FIGURE 3 is a back plan view thereof of FIGURE 1;
 FIGURE 4 is a top plan view thereof of FIGURE 1;
 FIGURE 5 is a bottom plan view thereof of FIGURE 1; and

FIGURE 6 is a side plan view thereof of FIGURE 1, the side opposite that shown in FIGURE 6 being identical to the side shown.

We claim:

The ornamental design for a carrier for bakery goods or the like, substantially as shown and described.
